FACING UNIT

Domenico Filangeri, Brooklyn, N. Y.

Application June 6, 1938, Serial No. 212,150

2 Claims. (Cl. 72—19)

This invention relates to certain new and useful improvements in bricks, tiles or the like for facing building walls and molds.

The primary object of the invention is to provide a brick or tile that is especially designed for use in covering or facing frame buildings to convert a frame building into a brick or tiled structure and the building element will herein-after be referred to as a brick.

10 A further object of the invention is to provide a novel construction of brick for the foregoing purpose wherein edges of the brick carry outwardly projecting lugs with the lugs of adjacent bricks being placed in end abutting contact and 15 with one side of each lug being in the plane of a side face of a brick while the opposite side of the lug is spaced from the opposite or outer face of the brick whereby all of the lugs are embedded in a mortar bedding or filling.

20 A still further object of the invention is to provide a mold or form for the production of a monolith of bricks and of a construction to permit correct mating placements of the monolith therein onto and into interfitting engagement with a previously laid monolith.

25 With the above and other objects in view that will become apparent as the nature of the invention is better understood, the same consists of the particular formation of brick with lugs carried thereby and the manner of laying the 30 bricks in a wall covering assembly.

In the accompanying drawing showing the preferred embodiments of the invention:

35 Figure 1 is a fragmentary elevational view of a wall construction of a frame building faced with bricks forming the subject of this invention and illustrating the spacer lugs carried by the bricks with a mortar filling between the bricks,

40 Figure 2 is a horizontal detail sectional view taken on line 2—2 of Figure 1, showing an end lug on one brick engaged with the end wall of an adjacent brick and a mortar covering for the lug,

45 Figure 3 is a vertical detail sectional view taken on line 3—3 of Figure 1, showing end abutting lugs carried by adjacent side edges of bricks with a mortar covering for the lug,

50 Figure 4 is a vertical detail sectional view taken on line 4—4 of Figure 1, showing the anchor nails for the foraminous sheet embedded in the cement or mortar base for the bricks,

55 Figure 5 is a perspective view of one of the bricks showing lugs projecting from opposite sides and one end of the brick,

Figure 6 is a plan view of a mold or form con-

taining a plurality of bricks for the production of a monolith for subsequent placement on a building wall,

Figure 7 is a fragmentary perspective view showing angular bricks with spacer lugs for corner work, and

Figure 8 is a fragmentary vertical sectional view of the mold for forming a monolith.

The brick or tile disclosed herein is especially designed for converting frame buildings into 10 brick or tiled structures and as shown in Figures 1 to 4, the wall of the frame building includes the usual wall boards 10 upon which the overlapped clapboards 11 are secured in the usual manner. A screen, metal lathing, or a foraminous sheet 12 is secured to the outer faces of the clapboards 11 by spikes or nails 13 that have their heads 14 as shown in Figure 4 projecting outwardly of the foraminous sheet 12 to be anchored in the cement or mortar base that fills 20 the interstices of the foraminous sheet and also forms a support for the bricks.

As shown in Figure 5, the brick 14 for flat wall construction is of rectangular formation and includes side edges 16 and ends 17. A plurality of suitably spaced lugs 18 projects outwardly of the side edges 16 of the brick with a pair of said lugs respectively at opposite ends of the side edges, while a single lug 19 projects from one end 17 only of a brick intermediate the side edges 16. The lugs are of rectangular formation and corresponding sides of the lugs 18 and 19 are in the plane of the inner face of the brick 16 while corresponding opposite faces of said lugs are spaced from the outer face of the brick as shown at 20 in several of the figures.

In facing a frame building with the bricks, it is preferable to form a plurality of the bricks into a monolith by means of the mold 21 shown in Figure 6, the bricks 15 being assembled in the mold 21 in the usual staggered arrangement with the inner faces thereof disposed downwardly and with side lugs 18 of adjacent bricks in end abutting engagement, a single end lug 19 being engaged with the plain end of an adjacent brick. The mold 21 is shaped as shown in Figure 6 for the reception of a combination arrangement of bricks, but it is to be understood that the mold 21 may be of other configuration to receive other combination arrangements of bricks. The bottom wall 21a of the mold carries inwardly extending lugs 21b that engage with the adjacent side lugs 18 of a brick 15 to provide an increased cement receiving area 21c at the side 16 of a brick between the lugs 18. The mold 21 as shown

in Figure 8 has a bottom board 21d slideable through the mold and the bricks with suitable face ornamentations are laid face downwardly upon said board 21 with cement poured thereover 5 to the desired depth and which cement is worked into the spaces 22 between the engaged lugs of adjacent bricks and into the spaces 21c. As shown in Figure 8 the upper side of the mold carries at the upper and lower edges thereof pairs 10 of spaced pins 21e. The monolith of bricks, before the cement has set together with the mold 21 with the cement backing 23, as shown in Figures 2 and 4, is engaged with and fills the interstices of the foraminous sheet 12, the pins 21e 15 of the mold engaging the clapboards 11 for correctly positioning the mold relative to the wall structure so that when pressure is exerted on the bottom board 21d of the mold, the monolith is projected from the mold as a unit for engagement with a previously laid monolith in correct 20 plumbing fashion. The mold 21 is then removed from the wall structure and additional cement may be filled into the spaces of the bricks 26 for completely covering the heads 14 of the nails 25 13 as shown at 24 in Figure 4, the cement overlying the sides 20 of the lugs 18 and 19 and being flush, if desired, with the outer faces of the bricks 15 for locking the bricks to the mortar bedding which in turn is locked to the foraminous sheet 30 12. The lugs 18 carried by the side edges 16 of the brick may be arranged in groups or spaced from each other in any manner desired, a preferable arrangement being illustrated.

In Figure 7, an angular form of brick is illustrated for corner work, but the brick is otherwise of substantially the same construction as the brick 15, a corner brick being shown at 15a 35 having an angular end extension 25, the opposite side edges of the corner brick carrying lugs 18a while a single lug 19a is carried by the outer 40 end of the extension 25. The lugs 18a and 19a

are related to the corner bricks 15a in a manner similar to the arrangement of the lugs 18 and 19 on the bricks 15, the mortar bedding and filling being associated with the corner bricks, the same as shown and described in connection with the 5 bricks 15.

From the above detailed description of the invention, it is believed that the construction and use thereof, will at once be apparent and while there are herein shown and described the preferred embodiments, it is nevertheless to be understood that various changes may be made therein as will fall within the scope of the invention as claimed.

I claim:

1. In bricks for use in covering the outer sides of frame structures, a brick of rectangular form, a relatively narrow lug projecting from at least one end of the brick, relatively narrow spaced lugs projecting from opposite side edges of the 20 bricks, the lugs being in the plane of the inner faces of the bricks and spaced from the plane of the outer face of the bricks, the bricks adapted to be laid in staggered relation with adjacent lugs abuttingly contacting, the sides and ends of the 25 bricks being free of projections between said lugs and a cement filling between the bricks and inclosing three sides of the lugs.
2. In a brick or tile of the character described, a brick body and relatively narrow spaced lugs 30 projecting from edges thereof and adapted for contact with lugs of adjacent bricks and said lugs being of less depth than the bricks with one side face in the plane of the inner face of the brick and the other side face spaced from the plane of the outer face of the brick, the sides and ends of the bricks being free of projections between said lugs, said bricks being of angular formation for corner work.
